ABSTRACT OF THE DISCLOSURE

A propping frame for mine galleries having two uprights slidably interconnected by two arms of a head-piece; the arms themselves are slidably clamped to two branches of a shoe; the branches are joined such as to form a pointed arch and are offset with respect to one another to permit the arms to assume an overlapping position.

It is known to construct propping frames for mining galleries of a head-piece and two uprights having a trough-shaped cross-section, said parts being interconnected by clamping members which allow their sliding under the action of the stresses exerted by the ground in which the gallery extends, while the head-piece is constituted by two arms having a radius of curvature which is substantially equal to that of the uprights and the two adjacent ends of which, possibly interconnected by an intermediate section, form with each other an angle which is substantially equal to that formed between the ends of the uprights when collapsed to the maximum extent.

Such frames are a substantial improvement over the conventional frames that include two uprights provided with an upper arcuate portion having a radius of curvature which is generally larger than that of the arcuate head-piece. Said improvement results in a reduction of the gaps arising between the ends of the head-piece and the uprights. The undesirable effects of such gaps, such as the permanent deformation of the frame components, are well known.

It has been found that the use of a head-piece in the shape of a pointed arch or ogive (full or truncated), as defined hereinabove, allows reducing the gap by about 90% in the case of pressures exerted substantially in the direction of the axis of symmetry of the frame. Now, in practice, the pressures are generally oblique, so that the preceedingly described arrangement, although a substantial improvement over prior frames, leaves room for further improvements with a view to still better absorb the stresses to which it is subjected.

My invention provides such an improvement and it covers a propping frame formed by at least two components assuming, when assembled, the shape of a complete or truncated ogive. The head-piece of the frame has two arcuate arms of substantially equal radius of curvature; the arms are mounted slidably with respect to each other and are slidably secured to a central shoe in such a manner that they are adapted to assume an overlapping position.

By virtue of said structure, the frame may, by proper selection of the radii and of the centers of curvature, slide under the action of oblique and vertical thrusts, or only under the action of oblique thrusts when the direction thereof is known in advance.

A prepared embodiment of my invention is illustrated by way of examples in the accompanying drawings where-

in:

FIG. 1 is a schematic side elevational view showing,

2

without any clamping members, of a propping frame according to my invention, wherein the two arms of the head-piece are slidably fitted in an ogive-shaped shoe;

FIG. 2 is an enlarged fragmentary view of the head-piece of the frame shown in FIG. 1 with the arms in a different position;

FIG. 3 is a front elevational view of the shoe shown in FIGS. 1 and 2;

FIG. 4 is a plan view of the shoe shown in FIG. 3; FIGS. 5 and 6 are sectional views taken along lines V—V and VI—VI of FIG. 3; and

FIG. 5a is a view of the shoe similar to FIG. 5 showing an arm of the head-piece clamped thereto.

The propping frame illustrated in FIG. 1 includes two trough-shaped, symmetrically arranged uprights P1 and P2 each having a rectilinear lower portion and an arcuate upper terminal portion having substantially the same radius of curvature. The upper, arcuate portions of the two uprights P1 and P2 are interconnected by a head-piece 15 formed of a central shoe S and arcuate arms B1, B2 slidably secured thereto and to the uprights. Shoe S includes two integral, symmetrically arranged arcuate branches b1 and b2 having substantially the same radius of curvature and being joined at an angle to form a unitary member 20 having an elevational outline of a pointed arch or ogive. The radius of curvature of arms B1 and B2 and of uprights P1 and P2 is substantially identical to that of branches b1 and b2. In case of maximum subsidence of the propping frame under action of external forces, the arcuate upper portions of uprights P1 and P2 will also form an ogive at an angle substantially the same as that of branches b1 and b2 of shoe S.

A thrust, oblique or otherwise, exerted by the ground, in which the gallery is formed, on a frame such as that 35 illustrated in FIG. 1, results in a sliding in shoe S of at least one of the arms B1, B2 to an extent as much as 0.80 to 1 meter without the appearance of any substantial gap between any of the uprights and the head-piece, and is usually followed by a relative sliding motion between the 40 ends of the arms B1 and B2 on the one hand and the corresponding ends of the respective uprights P1 and P2 on the other hand.

The central part of the head-piece is schematically 45 illustrated on a larger scale in FIG. 2 in which it will be remarked that the ends of the arms B1 and B2 engaging the respective branches b1 and b2 of the shoe S are in an overlapping position into which they may be urged by external forces acting, e.g. in the direction of arrows F shown in FIG. 1.

50 The reference characters e1 and e2 schematically indicate a clamping means such as a strap or a U-bolt mounted on branch b1 and b2 and adapted, when tightened, to frictionally but slidably urge arms B1, B2 against the respective branch b1, b2 of shoe S.

55 Turning now to FIGS. 3—6, there is shown the shoe S in more structural detail. The shoe S includes a central section 10 joining the juxtaposed end portions of branches b1 and b2 provided with two parallel troughs or upwardly open channels 8 and 9, respectively. The section of channels 8 and 9 is so designed that it preferably conforms to the contour of the arms B1 and B2 (FIG. 5a) disposed therein. Troughs 8 and 9 include, in the vicinity of their free end, bosses 11 and 13 perforated respectively at 12 and 14 to receive the legs of a clamping means e1 and e2 adapted to frictionally engage respective arms B1 and B2. As shown in FIG. 5a, a clamping means or U-bolt e2 extends transversally across trough 9 while its legs are received by openings 14—14 in boss 13. The threaded bolt ends projecting through openings 14, 14 are provided

60 with nuts 15, 15 which are suitably tightened to clamp arm B2 to branch b2 of shoe S. A similar assembly (not shown) is provided for branch b1.

A propping frame as described hereinabove may, under the action of vertical or substantially vertical pressures, subside first symmetrically and then, under the action of subsequent oblique thrusts, continue sinking with a simultaneous sliding of the shoe S and of that arm of the head-piece which is adjacent the point of origin of the pressure. The usual respective sliding displacement between the ends of the arms B1 and B2 on the one hand and the ends of the uprights on the other hand, occurs subsequently. By virtue of the parallel, offset arrangement of troughs 8 and 9, the arms B1 and B2 may assume an overlapping position as shown in FIG. 2.

Although a single embodiment of the invention has been depicted and described, it will be apparent that this embodiment is illustrative in nature and that a number of modifications in the apparatus and variations in its end use may be effected without departing from the spirit or scope of the invention as defined in the appended claims.

What I claim is:

1. A propping frame for mine galleries of the type including two uprights both having an upper arcuate terminal portion, a head-piece secured to said terminal portions and adapted to slide with respect to said uprights under the action of external forces, said head-piece has two arcuate portions joined in a pointed arch, the improvement in said head-piece comprising,

(A) a centrally positioned shoe having

- (1) two branches extending in opposite directions and having juxtaposed end portions joined together to form said shoe,
- (2) channel means extending arcuately in each of said branches, said channel means being parallel and offset with respect to one another,

5

10

15

20

25

30

(B) two oppositely extending arcuate arms each received in one of said channel means and adapted to slide therein in the length dimension thereof and assume an overlapping position with respect to one another, and

(C) clamping means secured to each branch for urging said arms into frictional engagement with the respective branches of said shoe.

2. The propping frame as defined in claim 1, wherein said channel means are upwardly open troughs.

3. The propping frame as defined in claim 2, wherein each of said clamping means includes a portion extending transversally over each of said troughs.

4. The propping frame as defined in claim 3, wherein said clamping means are constituted by U-bolts having leg portions received by openings in said branches on either side of said troughs.

5. The propping frame as defined in claim 1, wherein each channel and each arm disposed therein are of conforming cross-section.
